US00D765699S

(12) **United States Design Patent** (10) Patent No.: **US D765,699 S**
Alonso Ruiz et al. (45) Date of Patent: **** Sep. 6, 2016**

(54) **DISPLAY SCREEN OR PORTION THEREOF WITH GRAPHICAL USER INTERFACE**(71) Applicant: **Apple Inc.**, Cupertino, CA (US)(72) Inventors: **Marcos Alonso Ruiz**, San Francisco, CA (US); **Sebastian Johannes Bauer**, San Francisco, CA (US); **Jonathan Dascola**, San Francisco, CA (US); **Craig M. Federighi**, Los Altos Hills, CA (US); **Christopher Foss**, San Francisco, CA (US); **Jonathan P. Ive**, San Francisco, CA (US); **Chanaka Karunamuni**, Cupertino, CA (US); **Stephen O. Lemay**, San Francisco, CA (US)(73) Assignee: **Apple Inc.**, Cupertino, CA (US)(**) Term: **15 Years**(21) Appl. No.: **29/529,421**(22) Filed: **Jun. 6, 2015**(51) LOC (10) Cl. **14-04**
(52) U.S. Cl. **USPC D14/486; D14/488**(58) **Field of Classification Search**USPC **D14/485-495**
CPC **G06F 3/0481; G06F 3/04845; G06F 3/04817; G06F 17/212; G06T 13/80; G06T 15/02; H04N 1/00424**

Primary Examiner — Cathron Brooks*Assistant Examiner* — Cary M Robinson(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

The FIGURE is a front view of a display screen or portion thereof with graphical user interface showing our new design.

The outermost broken lines in the FIGURE show a display screen or portion thereof, and form no part of the claimed design.

The other broken lines in the FIGURE show portions of the graphical user interface that form no part of the claimed design.
